HONING MACHINE

Ernest F. Moon, Denver, Colo., assignor to Remington Arms Company, Inc., Bridgeport, Conn., a corporation of Delaware

Application September 16, 1943, Serial No. 502,565

7 Claims. (Cl. 51—170)

1

The present invention relates to an improvement in honing machines, particularly for the finishing or polishing of tools, dies, and the like, which require a highly polished precision surface. An object of the invention is to provide a tool of this character for both external and internal finishing operations, adapted to be conveniently hand operated, so as to permit of the effective controlled finishing of the work within extremely close tolerance limits, and by means of which the finishing operation may be carried out with better polishing results and in substantially less time than has heretofore been required with the use of buffing wheels and compounds.

A further object is to provide a honing machine adapted for convenient assembly with a hand-held power unit, in the form of an electric motor having a drive shaft projecting from a handle extension of the motor housing.

Another object is to provide a honing machine including one or more reciprocating honing stone elements, arranged for engagement with the work piece, and wherein yielding means is provided for engaging the stones with the work piece, to the end that the hand-held machine may be manipulated with a highly controlled degree of engaging pressure on the work piece.

With the above and other objects in view, embodiments of the invention are shown in the accompanying drawings, and these embodiments will be hereinafter more fully described with reference thereto, and the invention will be finally pointed out in the claims.

In the drawings—

Fig. 1 is a side elevation of a honing machine illustrating one form of the invention.

Fig. 2 is a longitudinal vertical sectional view thereof.

Fig. 3 is a transverse vertical sectional view, taken along the line 3—3 of Fig. 2.

Fig. 4 is a transverse vertical sectional view taken along the line 4—4 of Fig. 2.

Fig. 5 is a view partially in section and partially in side elevation, showing the tool illustrated in Figs. 1 to 4 engaged with the work piece.

Fig. 6 is a plan view of the inner side of one of the honing stone carrying sleeve members and the honing stone element carried thereby.

Fig. 7 is a plan view of a modified form of the invention.

Fig. 8 is a longitudinal vertical sectional view thereof, partially in side elevation, taken along the line 8—8 of Fig. 7.

Fig. 9 is a transverse vertical sectional view, 55

2

taken along the line 9—9 of Fig. 8, the honing stone elements being removed.

Fig. 10 is a transverse vertical sectional view, taken along the line 10—10 of Fig. 8.

Fig. 11 is a perspective view of the upper and lower stone carrying sleeve members in vertically separated relation.

Similar reference characters indicate corresponding parts throughout the several figures of the drawings.

10 In Figs. 1 to 6 there is illustrated a honing machine constructed in accordance with the invention, wherein a pair of oppositely reciprocating stone members are associated in the machine. The main supporting and driving parts are the 15 motor of the conventional type of hand tool, not shown, the extension arm 11 of its housing, and the box cam 14 carried by the motor shaft 13.

The main supporting sleeve 35 is secured to the cylindrical end 12 of the extension 11 by 20 means of a set screw 36, and is provided with a longitudinal guide slot 37 in its upper side. In the diametric lateral plane of the projecting end portion of the sleeve 35 there are provided a pair of opposed longitudinal slots 38—38, in which 25 are engaged key strips 39—39 extending into engagement with the cylindrical surface of the box cam 14.

A pair of spaced cylindrical surfaced stone 30 carrying sleeve members 40 and 41 are slidably engaged within the main supporting sleeve in surrounding relation to the cam and respectively above and below the key strips 39, the upper sleeve member 40 being provided with an inwardly projecting pin 42 engaging the cam track 16, and the lower sleeve member 41 being provided with an inwardly projecting pin 43 engaging the cam track in diametrically opposed relation to the pin 42. Rotation of the cam imparts opposite reciprocatory movement to the sleeve members.

To each of the sleeve members there is secured a honing stone 44, the connection means for which consists of an arm member 45 formed of 45 spring metal and secured in a recess 46 in the flat inner face of the forward end wall of the sleeve member by means of a screw 47, the projecting portion of the arm being provided with a pair of bayonet slots 48 in which are engaged bayonet hook portions 49 of a spring clip member 50 in which the inner end of the honing stone is engaged and secured. The outer surfaces of the honing stones are preferably cylindrical and of rounded tapered form at their outer ends.

A safety cover sleeve 51 is slidably engaged

about the main supporting sleeve 35, and is provided at its outer end with a flat forward wall 52 having a central aperture 53 therein through which the stones are adapted to be projected. A knob 54 is screwed into the cover sleeve and is provided with a screw portion 55 projecting inwardly into engagement with the slot 37 of the main supporting sleeve, the length of the slot determining the projected and retracted positions of the safety sleeve. Within the safety sleeve, between its forward wall and the outer end of the main supporting sleeve 35, there is provided a relatively light helical spring 56 which normally projects the cover member. Thus pressure upon the end of the safety sleeve against the face of the work projects the honing stones through the aperture 53 into engagement with the work, as shown in Fig. 5, the safety sleeve in this case serving to steady the position of the honing machine with respect to the work. The safety sleeve 20 may also be retracted by means of the knob, the pressure of the spring being sufficiently light so that it may be held in retracted position during the honing operation by a finger of the hand supporting the machine. In operation the honing stones are reciprocated rapidly in opposite directions, the springiness of the supporting arms 45 allowing them to yield slightly as they engage the work.

In Figs. 7 to 11 there is illustrated a modified form of the invention, wherein the honing stones are arranged for reciprocation at right angles to the axis of the motor shaft, this embodiment being particularly adapted for external honing, as for instance polishing of the cylindrical outer surface of a punch. A two part main supporting sleeve of generally cylindrical form is mounted upon the motor extension 11, the lower substantially semi-cylindrical sleeve part 57 being engaged about the lower half of the motor housing extension 11 with the cylindrical forward end portion 12 thereof fitting the inner cylindrical surface of the lower sleeve part, which is secured to the extension by means of a semi-circular clamp 58 encircling the upper half of the portion 12 and secured at its outwardly projecting flange portions 59 by screws 60 to ledge formations 61-61 provided upon opposite sides of the lower sleeve part. At its inner end the lower sleeve part is provided with a cylindrical band portion 62 for encircling engagement about the tapered surface of the extension 11 in proximity to the motor housing.

The upper substantially semi-cylindrical sleeve part 63 encloses the upper side of the extension 11 in opposed relation to the lower sleeve part, and is hingedly connected to the latter by means of hinge pins 64 having bearing in upwardly projecting hinge supporting plates 65-65 welded or otherwise suitably secured at opposite sides to the lower sleeve part. A semi-cylindrical recess 66 is provided in the inner surface of the upper sleeve part within which the clamp 58 is received. The upper and lower sleeve parts project forwardly a substantial distance from the end portion 12 of the motor housing extension 11, and are respectively provided with inwardly extending opposed end walls 67 and 68 having substantially semi-cylindrical recesses 69 and 70 therein forming a motor shaft passage coaxial with the motor shaft.

The honing stones are respectively carried upon the forward ends of the upper and lower supporting sleeve parts, and for this purpose each sleeve part is provided with a transverse slideway for-

mation, this slideway formation of the upper sleeve part consisting of an upper flat horizontal wall portion 71, and retaining slideway guide channels 72 and 73, the channel 72 being formed in the forward wall 67 and the channel 73 being formed in a forward inwardly extending flange portion 74 of the upper wall portion 71. The slideway of the lower sleeve part is of similar form, and comprises a lower flat horizontal wall portion 75, a slideway guide channel 76 formed in the forward wall 68 of the lower sleeve part and a slideway guide channel 77 formed in the inwardly extending forward flange portion 78 of the lower wall portion 75.

The upper stone carrying member is in the form of a box-like sleeve of generally rectangular form, and comprises an upper rectangular plate portion 79 slideably engaged at its longitudinal edges for transverse reciprocatory sliding movement in the guide channels 72 and 73, and having in its upper surface a relief recess 80. In forwardly spaced relation to its rearward edge the plate portion 79 is provided with a depending vertical wall 81 having a central vertically disposed cam receiving slot 82, and in rearwardly spaced relation to its forward edge is provided with a depending vertical wall 83, the upper stone 84, of generally rectangular form, being engaged between the walls 81 and 83 and secured therein by means of set screws 85 in the forward wall 83. The stone is provided with a suitable work engaging surface, consisting in the illustrated embodiment of a central V-groove 86 extending parallel to the direction of reciprocation of the stone.

The sleeve for carrying the lower honing stone comprises a rectangular bottom plate portion 87 engaged at its longitudinal edges with the slideway guide channel 76 and 77, and having in its under surface a relief recess 88. In forwardly spaced relation to its rearward edge the bottom plate portion 87 is provided with an upstanding vertical wall 89, recessed at its forward side as at 90 to provide a relatively thick lower portion, the inwardly disposed shoulder ledge of which is vertically opposed to the wall 81 of the upper sleeve, and a relatively thinner upper wall portion inwardly offset from the wall 81 of the upper sleeve and overlapping it. This relatively thinner upper wall portion is provided centrally with a vertical cam receiving slot 91. In rearwardly spaced relation to its forward edge the bottom plate portion 87 is provided with an upstanding vertical wall 92, the lower honing stone 93 being engaged between this wall and the relatively thick lower part of the wall 89 and secured therein by set screws 94 in the forward wall 92. The lower honing stone 93 is of identical form with the upper stone, and is provided centrally with a V-groove 95 opposed to the V-groove 86 of the upper stone. In order to balance the weight of the lower sleeve with the upper sleeve, the lower sleeve is provided with a rectangular opening 96 in its lower plate portion 87 and a series of cylindrical holes 97 in the relatively thick lower part of the wall 89.

Upon the forward screw threaded end of the motor shaft 13 there is engaged an internally threaded cam arbor 98, fixed in position by means of a lock nut 99 and extending at its forward reduced diameter portion 100 through the passage provided by the recesses 69 and 70 of the upper and lower supporting sleeve parts, being provided upon its reduced diameter forwardly projecting end portion 101 with eccentrically mounted circular cams 102 and 103 positioned

5

in spaced relation by a spacing washer 104, these cams being set so that they are eccentric in diametrically opposite directions. The cam 102 is engaged in the slot 82 of the upper stone carrying sleeve member and the cam 103 is engaged in the slot 91 of the lower stone carrying sleeve member, the cam diameters corresponding to the widths of the slots. Thus rotation of the motor shaft causes the cams to impart rapid reciprocatory movement to the stone carrying sleeves in opposite directions.

In operation the honing stones have the work piece engaged between them in the V-grooves 86 and 95, the work piece being preferably rotated slowly during the honing operation. For the purpose of engaging the work piece between the stones, as well as to accommodate work pieces of different diameters and to apply compressive pressure of the stones upon the work piece, the upper supporting sleeve part is adapted to have swinging movement with respect to the lower sleeve part about the hinge support 64, without disturbing the cooperative engagement of the cam 102 in the slot 82, so that the reciprocating actuation of the stones takes place in any position of the relative swinging adjustment between the two stones.

Yielding pressure is applied between the upper and lower supporting sleeve parts, and for this purpose a tension clamp is provided comprising a yoke 105 secured at its side arms by means of screws 106 in flat-surfaced recesses 107-107 provided in the opposite sides of the lower sleeve part contiguous to its forward end, this yoke member being disposed in arched spaced relation to the upper sleeve part. An internally threaded tubular spring supporting bushing 108 is screwed in a threaded hole 109 provided centrally in the yoke, and is provided with an adjustable pressure screw 110, a helical tension spring 111 being engaged at its upper end within the lower portion of the passage through the bushing 108 and at its lower end in a circular pocket 112 provided in the upper side of the upper sleeve part 63. This spring presses the upper honing stone 84 toward the lower honing stone 93, and permits opening of the stones to engage the work between them and to accommodate work of different diameters. By adjusting the screw 110 the tension of the spring may be regulated to apply greater or less compressive pressure of the stones upon the work being polished.

The form of the invention illustrated in the drawings and described herein is typical and illustrative only and it is evident that the invention is capable of embodiments in other forms, all falling within the scope of the appended claims, which are to be broadly construed.

What is claimed is:

1. In a finishing tool, a drive unit including a housing and a rotatable drive shaft mounted therein, cam means on said drive shaft, a supporting sleeve engaged about said housing and including a portion from said housing in surrounding relation to said cam means and constituting slideway guide means arranged parallel to the axis of said drive shaft, a tool carrier mounted for reciprocation in said guide means, cam engaging means carried by said tool carrier and engaged with said cam means, whereby rotation of said cam means imparts reciprocation to said tool carrier, a tool carried by said tool carrier projecting forwardly therefrom, and a spring projected tubular protective cover member slid-

6

ably engaged with said supporting sleeve and having an apertured forward end through which said tool is adapted to be projected through retraction of said cover member.

5 2. In a finishing tool, a drive unit including a housing and a rotatable drive shaft mounted therein, cam means on said drive shaft, a supporting member engaged with said housing, slideway guide means carried by said supporting member and arranged parallel to the axis of said drive shaft, a pair of oppositely arranged tool carriers mounted for reciprocation in said guide means, and cam engaging means respectively carried by said tool carriers and engaged with said cam means, whereby rotation of said cam means imparts simultaneous reciprocation to said tool carriers in opposite directions.

20 3. In a finishing tool, a drive unit including a housing and a rotatable drive shaft mounted therein, cam means on said drive shaft, a supporting sleeve engaged about said housing and including a portion projecting from said housing in surrounding relation to said cam means and constituting slideway guide means arranged parallel to the axis of said drive shaft, a pair of oppositely arranged substantially semi-cylindrical tool carriers mounted for reciprocation in said guide means, and cam engaging means respectively carried by said tool carriers and engaged with said cam means, whereby rotation of said cam means imparts simultaneous reciprocation to said tool carriers in opposite directions.

25 4. In a finishing tool, a drive unit including a housing and a rotatable drive shaft mounted therein, cam means on said drive shaft, a supporting member engaged with said housing, slideway guide means carried by said supporting member and arranged parallel to the axis of said drive shaft, a pair of oppositely arranged tool carriers mounted for reciprocation in said guide means, springy tool mount members respectively carried by said tool carriers yieldable toward and away from each other, tools respectively carried by said tool mount members, and cam engaging means respectively carried by said tool carriers and engaged with said cam means, whereby rotation of said cam means imparts simultaneous reciprocation to said tool carriers in opposite directions.

30 5. In a finishing tool, a drive unit including a housing and a rotatable drive shaft mounted therein, cam means on said drive shaft, a supporting member engaged with said housing, a pair of opposed slideway guide means carried by said supporting member arranged transversely at right angles to the axis of said drive shaft, tool carriers mounted respectively for reciprocation in said guide means, and cam engaging means respectively carried by said tool carriers and engaged with said cam means, whereby rotation of said cam means imparts simultaneous reciprocation to said tool carriers in opposite directions.

35 6. In a finishing tool, a drive unit including a housing and a rotatable drive shaft mounted therein, cam means on said drive shaft, a supporting member engaged with said housing, a pair of opposed slideway guide means carried by said supporting member arranged transversely at right angles to the axis of said drive shaft, one of said guide means being movable toward and away from the other guide means, spring means arranged to exert pressure on said movable guide means toward said other guide means, tool carriers respectively mounted for reciprocation in said guide means, and cam engaging

means respectively carried by said tool carriers and engaged with said cam means, whereby rotation of said cam means imparts simultaneous reciprocation to said tool carriers in opposite directions.

7. In a finishing tool, a drive unit including a housing and a rotatable drive shaft mounted therein, a pair of oppositely eccentric axially spaced cams on said drive shaft, a supporting member engaged with said housing, a pair of opposed slideway guide means carried by said sup-

porting member arranged transversely at right angles to the axis of said drive shaft, tool carriers respectively mounted for reciprocation in said guide means, and cam engaging means respectively carried by said tool carriers and respectively engaged with said cams, whereby rotation of said cams imparts simultaneous reciprocation to said tool carriers in opposite directions.

ERNEST F. MOON.
